UNITED STATES PATENT OFFICE.

ERNST G. ANDERSON, OF WESTFIELD, NEW JERSEY, ASSIGNOR TO NATIONAL PNEUMATIC ACTION CO., INC., OF NEW YORK, N. Y., A CORPORATION OF NEW YORK.

AUTOMATIC MUSICAL INSTRUMENT

1,208,723.

Specification of Letters Patent. Patented Dec. 19, 1916.

Application filed June 19, 1914. Serial No. 846,030.

To all whom it may concern:

Be it known that I, ERNST G. ANDERSON, a citizen of the United States, and a resident of Westfield, in the county of Union and State of New Jersey, have invented certain new and useful Improvements in Automatic Musical Instruments, of which the following is a specification.

The invention pertains to player-pianos, and resides more particularly (1) in a novel organization and arrangement of the valve-chest, pneumatics, conduits and co-acting parts of a player-piano whereby a simplified, compact and highly efficient instrument capable of ready application to a piano case is produced, and (2) in a special construction of the valve features of the valve-chest whereby the bridges and wires commonly used for guiding the valves are dispensed with, a uniform throw of the valves is assured and the construction of this part of player-pianos is, as a whole, simplified and rendered uniformly efficient.

The invention will be fully understood from the detailed description hereinafter presented, reference being had to the accompanying drawings, in which:

Figure 1 is a substantially central vertical transverse section, partly broken away, through a player-piano embodying my invention; Fig. 2 is a front elevation, partly broken away, of a portion of the same, this figure also showing a portion of the sides of a piano case and the usual shoulders on the inner faces thereof which I utilize as supports for my instrument; Fig. 3 is a vertical transverse section through a portion of the same taken on the dotted line 3-3 of Fig. 2, and Fig. 4 is a horizontal section, partly broken away, through a portion of the same taken on the dotted line 4-4 of Fig. 1.

In the drawings, 10 designates portions of the sides of a piano-case of the usual type, 11 brackets on the inner faces thereof whose upper edges afford supporting shoulders for my instrument which is made to rest thereon; 12 the customary music-box, 13 the tracker-bar, 14 the usual perforated music-sheet, 15 the lower roll or spool for said sheet, 16 the bleed strip below the music box, 17 the valve-chest, 18 the upper row or series of pneumatics, and 19 the lower row or series of pneumatics, the lower movable members of which two series of pneumatics

are operatively connected with the abstracts 20 of the piano action in a well-known or any suitable manner.

The bleed strip 16 is connected with the tracker-bar 13 by the customary tubes or conduits 21, and at the front of said strip is formed a continuous air chamber or channel 22 in communication with all the bleed-openings 23 and also in communication with the main chamber 24 of the valve-chest 17 through one or more tubes or conduits 25.

The valve-chest 17 rests, at its ends, on the brackets 11 (Fig. 2), and the main chamber 24 of said chest is connected, as usual, with the main bellows, not shown, by a lead or tube 26. The valve-chest 17 has in its bottom two parallel series of chambers 27 closed at their upper ends by diaphragms 28 of known character and utility in this art, and said chambers 27 are respectively in communication with the transverse ports 29 in the bleed strip 16 through connecting tubes or conduits 30, there usually being eighty-eight of said ports and an equal number of said tubes or conduits.

In the top of the valve-chest 17 and directly over the chambers 27 are two parallel series or rows of vertical chambers 31, the chambers in one series or row being in staggered relation to the chambers in the other series or row, as shown in Fig. 4. The chambers 31 are preferably, though not necessarily, circular in cross-section, and each of said chambers contains a vertically movable valve 32 which is preferably, when the chamber is circular, polygonal in cross-section and fitted to freely guide at its angles on the wall of the chamber and leave air spaces between its sides and said wall. One point of this feature of the invention consists in having the chambers 31 different in outline from the valves 32 so that the valves may directly guide on the walls of the chambers and leave air spaces at their sides within the chambers. The valves 32 are less in vertical length than the chambers 31 so that they may have a vertical movement therein, and each of said valves carries a central stem 33 having on its lower end a head in engagement with a diaphragm 28 below the valve. I make the valves 32 in the form of blocks of wood.

At the upper and lower ends of the chambers 31 there are secured, by glue or otherwise, upon the upper and lower surfaces of

the top of the valve-chest, blocks 34 having central openings therethrough which are less in diameter than the valves 32 and which blocks serve to retain said valves within said chambers. The facing sides of the blocks 34 have pieces of leather or the like secured thereon to coöperate with the respective ends of the valves 32 in forming effective joints when said valves are in their respective upper and lower positions. The valve-stems 33 extend into or through the openings in the blocks 34 but do not operate to guide the valves 32, as has heretofore usually been the case. There is a distinct advantage in facing the blocks 34 with leather or equivalent material instead of facing the ends of the valves 32 with such material, since in my construction any variations in the thickness of the leather facings do not render the throw of the valves irregular, whereas if the leather facings were on the ends of the valves and varied in thickness such variations would necessarily modify the throw of the valves.

25 The upper stationary members of the upper series of pneumatics 18 are secured to the bottom of the valve-chest 17, and said pneumatics 18 are respectively placed in communication with the rear series of vertical chambers 31 by means of a rearwardly disposed set of tubes 35 whose lower ends communicate directly with said pneumatics through openings in the upper members thereof.

30 The upper stationary members of the lower series of pneumatics 19 are secured to the bar 36, and said pneumatics 19 are respectively placed in communication with the front series of vertical chambers 31 by means of a forwardly disposed set of tubes 37 whose lower ends communicate directly with said pneumatics through openings in the upper members thereof. Both the tubes 35 and 37 communicate directly with their respective pneumatics 18, 19. When the tubes 37 have a direct communication with their pneumatics 19, the latter may be shifted as required on the lower side of the board 36 so as to position them with respect to the requirements to be met.

35 The operation of my player piano will largely be understood from the foregoing description without detailed explanation. It will be appreciated by those familiar with player pianos that the action of the main bellows, not shown, will during playing maintain through the tube or conduit 26 a partial vacuum in the valve-chest 17 and, through the tube 25, in the chamber 22 at the front of the bleed-strip 16, this condition existing while all of the valves 32 are dormant. The valves 32 are held in their dormant position by the vacuum in the valve-chest 17 and from the fact that there is a bleed from the chamber at the front of the bleed-strip down through the tubes 30 to the chambers 27 below the diaphragms 28.

40 The vacuum in the valve-chest 17 acts against the lower faces of the valves 32 to hold said valves down, the stems of said valves depressing the diaphragms. When a note aperture in the music-sheet uncovers a hole in the tracker-bar, atmospheric air will flow through said hole and down through its tube 21 and thence through the bleed-strip and proper tube 30 to the chamber below a diaphragm 28 of the valve-chest 17, causing the diaphragm to push the valve 32 upwardly to its open position. This opening of the valve 32 closes the outlet port 80 or opening through the block 34 above said valve and then the exhaust or vacuum in the chest 17 acts through either a tube 35 or a tube 37, as the case may be, and exhausts the air from within the proper pneumatic, 85 causing the movable member of the pneumatic to move upwardly and effect the sounding of the note. The ports through the blocks 34 above the chambers 31 and valves 32 are normally open to allow atmospheric air to flow through the conduits 35, 37 to the pneumatics, but when the valves 32 become elevated the ports or openings through the blocks 34 become closed and then the vacuum or exhaust in the valve-chest 17 may act through the proper tubes 35, 37 to actuate the pneumatics and the abstracts 20 connected therewith. There are usually eighty-eight holes in the tracker-bar, eighty-eight valves 32, and eighty-eight pneumatics, there being forty-four pneumatics in the upper row and forty-four in the lower row, with each pneumatic connected by a tube with a chamber 31 for one of the valves 32. When a valve 32 is elevated the exhaust through the valve-chest 17 acts on the proper pneumatic to effect the striking of the note, and when the hole in the tracker-bar is closed by the music-sheet so as to cut off air from the tube or tubes 21 which may have been in operation, the valve or valves 32 will immediately descend and open the upper ends of the tube or tubes 35, 37 to the atmosphere, thereby restoring the pneumatics to their normal or dormant condition.

45 An important part of my invention resides in the compact and non-complex construction and organization of the features of the player piano adapting the same to be readily applied to the piano case, and as a part of this organization I would call attention to the fact that the valve chambers 31 in the top of the valve-chest 17 are evenly divided with respect to each other and are in two parallel rows, with the tubes 35 from the rear row all extending rearwardly to their pneumatics 18, and the tubes 37 all extending from the front row of valve chambers 31 to their pneumatics 19. The 105

50 110 115 120 125 130

tubes 30 from the bleed-strip 16 are all at the front of the valve chest 17 and at their lower ends some of the tubes 30 extend into the front row of chambers 27 and others extend to the rear row of chambers 27, the valves 32 being arranged in staggered order and thereby permitting the proper tubes 30 to reach the rear row of chambers 27.

A very important feature of the invention 10 resides in the fact that the valves 32 guide on the walls of the chambers 31, and that said valves differ in outline from the outline in cross-section of said chambers 31. A further advantageous feature of the construction also is that the upper and lower 15 surfaces of the valves 32 are left plain, and that the leathers or packings to coöperate with the valves in forming air-tight joints, are on the blocks 34 in lieu of being on the 20 valves.

What I claim as my invention and desire to secure by Letters Patent, is:

1. In a player-piano comprising a tracker-bar for a perforated traveling music-sheet 25 and a bleed-strip connected by tubes therewith, a valve chest comprising an exhaust chamber and having in its top parallel rows of valve chambers and vertically movable valves therein and in its bottom, below said 30 valves, parallel rows of chambers and diaphragms covering the same and in engagement with stems of said valves, a series of tubes connecting the bleed-strip with said diaphragm chambers, a row of pneumatics 35 at the lower side of said valve chest, rearwardly disposed tubes extending from the rear series of valve chambers in the top of the valve chest to said pneumatics, a board 40 extending below said pneumatics, a row of pneumatics at the lower side of said board, and a series of frontwardly disposed tubes 45 connecting the front row of valve chambers in the top of the valve chest with said lower pneumatics, said frontwardly disposed tubes 50 communicating directly with the lower pneumatics through the stationary upper members thereof, and the movable members of both pneumatics being connected with the abstracts of the piano action.

2. In a player-piano comprising a tracker-bar for a perforated traveling music-sheet and a bleed strip connected by tubes therewith, a valve-chest comprising an exhaust chamber and having in its top parallel rows of valve chambers and vertically movable valves therein and in its bottom, below said valves, parallel rows of chambers and diaphragms covering the same and in engagement with stems of said valves, a series 55 of tubes connecting the bleed strip with said diaphragm chambers, a row of pneumatics at the lower side of said valve chest, rearwardly disposed tubes extending from the 60 rear series of valve chambers in the top of

the valve chest to said pneumatics, a board extending below said pneumatics, a row of pneumatics at the lower side of said board, and a series of frontwardly disposed tubes connecting the front row of valve chambers 70 in the top of the valve chest with said lower pneumatics, said frontwardly disposed tubes communicating directly with the lower pneumatics through the stationary upper members thereof and the movable members of 75 both pneumatics being connected with the abstracts of the piano action, and all of the said tubes connecting the bleed strip with said diaphragm chambers being at the front of the valve-chest. 80

3. In a player-piano comprising a tracker-bar for a perforated traveling music-sheet and a bleed-strip connected by tubes therewith, a valve chest comprising an exhaust chamber and having in its top parallel rows of valve chambers and vertically movable valves therein and in its bottom, below said valves, parallel rows of chambers and diaphragms covering the same and in engagement with stems of said valves, a series of 90 tubes connecting the bleed strip with said diaphragm chambers, two rows, one below the other, of pneumatics below said valve chest, a rearwardly disposed set of tubes extending from the rear series of valve-chambers in the top of the valve chest to one row of said pneumatics, and a frontwardly disposed set of tubes extending from the front series of chambers in the top of the valve chest to the other row of said pneumatics. 100

4. In a player-piano comprising a tracker-bar for a perforated traveling music-sheet and a bleed strip connected by tubes therewith, a valve chest comprising an exhaust chamber and having in its top parallel rows of valve chambers and vertically movable valves therein and in its bottom, below said valves, parallel rows of chambers and diaphragms covering the same and in engagement with stems of said valves, a series of tubes connecting the bleed strip with said diaphragm chambers, two rows, one below the other, of pneumatics below 105 said valve chest, a rearwardly disposed set of tubes extending from the rear series of chambers in the top of the valve chest to one row of said pneumatics, and a frontwardly disposed set of tubes extending from the front series of chambers in the top of the valve chest to the other row of said pneumatics. 110

5. In a player-piano, a pneumatic valve-action comprising a valve-chest having in the top thereof a series of vertical chambers with tubes leading from the sides thereof to the pneumatics, apertured blocks secured to the upper and lower sides of said 125 130

- top and partly closing the upper and lower ends of said chambers, and a set of valves confined within said chambers, the body portion of said valves being fitted to guide directly on the walls of said chambers and differing in outline therefrom.
6. In a player-piano, a pneumatic valve action comprising a valve-chest having in the top thereof a series of vertical chambers with tubes leading from the sides thereof to the pneumatics, apertured blocks secured to the upper and lower sides of said top and partly closing the upper and lower ends of said chambers, and having packing material secured on their facing sides, and a set of vertically movable valves confined within said chambers and adapted in their respective positions to engage said blocks for closing the openings therein, said chambers being circular in cross-section and the body portion of said valves being polygonal in cross-section and fitted to guide directly on the walls of said chambers.
7. In a player-piano, a pneumatic valve action comprising a valve-chest having in

the top thereof a series of vertical chambers with tubes leading from the sides thereof to the pneumatics, apertured blocks secured to the upper and lower sides of said top and partly closing the upper and lower ends of said chambers, and having packing material secured on their facing sides, and a set of vertically movable valves confined within said chambers and adapted in their respective positions to engage said blocks for closing the openings therein, said chambers being circular in cross-section and the body portion of said valves being polygonal in cross-section and fitted to guide directly on the walls of said chambers.

Signed at New York city, in the county of New York and State of New York, this 18th day of July, A. D. 1914.
